Primary Examiner — Michael A Maharajh*(74) Attorney, Agent, or Firm* — Patshegen IP; Moshe Pinchas(57) **CLAIM**

The ornamental design for a vibrator as shown and described.

DESCRIPTION

The applicant has invented a new design for a vibrator as set forth in the following drawings:

FIG. 1 is a left side view of a vibrator showing the new design, the right side view is a mirror image thereof;

FIG. 2 is a front view of the vibrator of FIG. 1.

FIG. 3 is a top view of the vibrator of FIG. 1.

FIG. 4 is a side perspective view of the vibrator of FIG. 1.
